UNITED STATES PATENT OFFICE.

NELS G. EK, OF MINNEAPOLIS, MINNESOTA, ASSIGNOR TO FOSSTON-CARPENTER COMPANY, OF ST. PAUL, MINNESOTA, A CORPORATION OF MINNESOTA.

GRAIN-SIEVE.

1,305,267.

Specification of Letters Patent. Patented June 3, 1919.

Application filed September 29, 1917. Serial No. 193,940.

To all whom it may concern:

Be it known that I, NELS G. EK, a citizen of the United States, residing at Minneapolis, in the county of Hennepin and State 5 of Minnesota, have invented certain new and useful Improvements in Grain-Sieves; and I do hereby declare the following to be a full, clear, and exact description of the invention, such as will enable others skilled 10 in the art to which it appertains to make and use the same.

My present invention relates to fanning mills and is directed to the provision of simple and efficient means for imparting move- 15 ments to the various reciprocating parts of the mill or machine. To the above ends, generally stated, the invention consists of the novel devices and combinations of de- 20 vices hereinafter described and defined in the claims.

In the accompanying drawings which illustrate the invention, like characters indicate like parts throughout the several views.

25 Referring to the drawings,

Figure 1 is a view in side elevation showing the improved fanning mill;

Fig. 2 is a vertical section taken from front to rear and centrally through the ma- 30 chine;

Fig. 3 is a front end elevation of the lower portion of the machine showing parts in the vicinity of the line marked 3—3 on Fig. 1;

Fig. 4 is an enlarged section taken on the 35 line 4—4 of Fig. 1; and

Fig. 5 is a transverse section taken on the line 5—5 of Fig. 1.

The fanning mill comprises a suitable framework 6, an overhead feed hopper 7, 40 an upper sieve-equipped shoe 8, a lower sieve-equipped shoe 9 and a fan made up of a casing 10 and fan head 11 working therein, all of which parts are, or may be assumed to be, of the customary construction.

45 The upper shoe 8 is mounted for trans- verse vibratory movements and, as shown, is suspended from the sides of the hopper 7, by yielding metal straps 12. This upper shoe also carries a gang of sieves 13, such as 50 usually provided for the separation of the wheat and oats, the latter being tailed off while the wheat passes through the same and onto a screen sieve 14 that is carried by the lower shoe 9. The fan case 10 is open 55 on that side that faces the sieves and is ar-

ranged to direct a blast of air against the said sieves in the usual way. The lower shoe 9 is mounted and reciprocated longitudinally of the machine and in the direction of the travel of the stock over the screen 60 14, and, as shown, it is thus mounted to slide between side boards 15 fixed to the frame 6 and to slide on transverse bars 16 rigidly secured to said side boards.

Mounted in suitable bearing brackets 17 65 on the frame 6 is a rock shaft 18 that has a pair of upwardly projecting arms 19 to which a head bar 20 is pivotally connected at its ends. This head bar 20 is adapted to align with the upper transverse bar of the 70 shoe 9 and it has a rigidly secured metallic plate 21, which, by a coupling pin 22 and coöperating cotter, is adapted to be coupled to the said shoe 9, as best shown in Fig. 2. Preferably, the coupling plate 21 is pro- 75 vided with upturned flanges 21^a that lie close to, but out of contact with the side boards 15. A deflecting bar or narrow blade 23 has end lugs that are pivotally connected to the end flanges 21 at 24. 80

At one end, (see Figs. 1 and 5), the rock shaft 18 is provided with an upwardly projected arm 18^a, which, by means of a long pitman or connecting rod 25, is connected to a crank 26 (see Fig. 2), that is secured 85 to one end of the shaft 11^a of the fan head 11. At its opposite end, the fan shaft 11^a is provided with a crank disk in the form of a sprocket 27 which carries a crank pin 28. Mounted on one side of the frame 6, and as 90 shown, working in a slot 6^a thereof, (see Fig. 1), is a bell crank 29. One arm of the bell crank 29 is connected by a crank rod 30 (see Figs. 1 and 2) to a lug 31 on the far side of the upper shoe 8, and the other arm 95 of said bell crank is connected to one end of a pitman or crank rod 32, the head or opposite end of which pitman 32 is mounted on the crank pin 28. A supplemental head 33 in the form of a star-shaped metal plate 100 is rigidly secured to the head of the pitman 32 and the upper and lower portions of this supplemental head are pivotally connected, respectively, to the lower end of a crank rod 34 and to the upper end of a crank 105 rod 34^a.

Working in the discharge opening of the hopper 7 is a pair of coöperating gates 35 and 36. The gate 35 has a shaft 35^a that projects at one end and is provided with an 110

arm 37 that is pivotally connected to the upper end of the crank rod 34. The shaft 36^a of the gate 36 projects at one end and is provided with an arm 38, the head of which 5 is engaged by an adjusting screw 39 that is swiveled in a bearing 40 on one side of the hopper 7. By adjustments of the screw 39, the gate 36 may be set vertically in different positions in respect to the free edge of 10 the gate 35, so as to thereby regulate the amount or rate of flow of the grain from the hopper to the sieves. When the machine is in operation, the gate 35 is vibrated so as to produce an agitation necessary to insure 15 the continuous and even flow of the grain.

Receiving from the lower end of the scalping screen 14 is a transversely inclined discharge trough 41 that is hung for endwise vibratory movements on a pair of U-shaped hanger rods 42 and 43. These hanger rods 42 have a crank-like action, their short arms being pivoted to strips on the sides of the trough and their long arms being pivoted in the adjacent corner posts 25 of the frame 6. The long arm of the hanger rod or crank 43 has an arm 44 that is pivotally attached to the lower end of the above noted crank rod 34^a.

The machine shown is arranged to be 30 driven by hand power, and hence, is provided with a large driving sprocket 45 loosely journaled on a shaft 46 that is held by brackets 47 on the sides of the hopper 7. This sprocket 45 is provided with an operating crank or handle 48, by means of which 35 it may be rotated. A sprocket chain 49 runs over the sprocket 45 and over the small sprocket 27 of the fan shaft 11^a. It will, of course, be understood that this machine may, if desired, be driven by an electric motor or other power device. The salient feature of the invention resides in the simple and efficient means for vibrating the sieves and various other moving parts. 40

45 Obviously, when the fan is driven, either by hand power, or otherwise, the following movements will be automatically transmitted, to wit, through the pitman 25, the lower sieve shoe 9 will be vibrated longitudinally 50 of the machine; through the pitman 32, the

upper shoe 8 will be vibrated transversely of the machine; through the crank rod 34, the vibratory feed gate 35 will be oscillated; and through the crank rod 35, the discharge trough 41 will be given an endwise vibratory movement which will insure the travel of the stock over the same and off from the discharge end thereof. Thus, all of the various moving parts of the machine are driven from the fan shaft, and moreover, three of 60 the vibratory movements are transmitted from one crank, to wit, from the crank pin 28.

What I claim is:

1. In a fanning mill, the combination 65 with a fan having a shaft with a crank head at one end, of a vibratory sieve-equipped shoe, a vibratory feed device, a vibratory discharge trough, a pitman connected to said crank and to said shoe, and two connecting 70 rods pivoted to the head of said pitman at points offset from the axis of the pivotal connection between said crank and pitman head, the one being connected to said feed device and the other to said trough, whereby 75 said shoe, feed device and trough are vibrated from the single crank carried by the fan shaft.

2. In a fanning mill, the combination 80 with upper and lower vibratory sieve-equipped shoes, of a fan having a shaft with a crank at each end, a pitman at points offset from the axis of the pivotal connection between said crank and pitman head connected to one of said cranks and to one 85 of said shoes, a pitman connected to the other of said cranks and to the other of said shoes, a vibratory feed device, a vibratory discharge trough, and two crank rods pivoted to the head of said second noted pitman, one of said crank rods being connected to said feed device and the other to said trough. 90

In testimony whereof I affix my signature in presence of two witnesses.

NELS G. EK.
